CENTER JOINT FORM

Robert R. Robertson, Chicago, Ill.

Application January 16, 1946, Serial No. 641,470

2 Claims. (CL 94—17)

1

This invention pertains to concrete construction joints, and more particularly to road center joint forms constructed to permit the road slabs forming opposite lanes of a road to be tied together without the use of the ordinary types of tie bars.

The improved center joint form of this invention is adapted to be placed longitudinally along the center line of a road subgrade, and said form is punched out or cut to provide a plurality of anchoring units which are so constructed that they may be pivotally swung out of the plane of the form into positions at right angles thereto to provide anchoring lugs or wings projecting from opposite sides of the form to be embedded in the concrete forming the slabs of the adjacent road lanes to tie the lanes together without necessitating the use of the ordinary types of tie bars.

It is an object of this invention to provide an improved and simplified form of center joint form consisting of a main body or plate having integrally formed thereon anchoring means which are adapted to be swung out of the plane of the form to project in opposite directions from the form to facilitate tying of the opposite slabs together when the form is embedded in concrete which forms the slabs of adjacent road lanes.

A further object of the invention is the construction of a center joint form wherein the form plate has cut or struck therefrom a plurality of anchoring members which are so formed that they have an integral connection with the body of the form permitting the anchoring members to be pivotally swung out of the plane of the form into positions at right angles thereto, said anchoring members being so formed that they may be pivotally swung so that adjacent anchoring members may be reversed with respect to one another if desired.

It is also an object of this invention to provide an improved and simplified form of center joint form in which anchoring members are hingedly formed out of the material of the form to permit the anchoring members to be pivotally swung in either direction to project from opposite sides of the form to position the anchoring members either vertically or horizontally at right angles to the plane of the form, depending upon whether the anchoring members are swung longitudinally or transversely with respect to the form.

It is furthermore an object of this invention to provide a road joint form of simple and effective construction wherein the body of the form may be either a flat plate, or a plate formed with

2

channels or beads, said body of the form, whether plain or channeled, adapted to have anchoring members integrally formed therewith and so connected to the form body that the anchoring members may be pivotally swung in one direction or another to permit opposite ends of the anchoring members to project from opposite sides of the form body and serve as anchoring means for tying the slabs of adjacent road lanes together.

It is an important object of this invention to provide a road joint form wherein a body plate has cut therefrom a plurality of anchoring members each consisting of two blades of different shapes disposed in the same plane and adapted to be projected from opposite sides of the form plate by simply hingedly swinging the anchoring members out of the plane of the plate on integral connections joining the anchoring members with the plate.

It is an important object of this invention to provide a road joint form consisting of a body plate adapted to be supported on a road subgrade by any suitable standard means with said plate having cut or formed therefrom a plurality of anchoring members each consisting of oppositely projecting anchoring blades disposed in the same plane and adapted to be projected from opposite sides of the joint plate into either vertical or horizontal planes, depending upon the positioning of the anchoring members with respect to the body plate.

Other and further important objects and features of the invention will be apparent from the disclosures in the specification and the accompanying drawings.

The invention (in preferred forms) is illustrated in the drawings and hereinafter more fully described.

On the drawings:

Figure 1 is a fragmentary vertical detail section transversely across the middle portion of a concrete road, the opposite lane slabs of which are indicated in dotted lines and are separated by means of a center joint form embodying the principles of this invention and providing a means for tying the opposite slabs together without the use of tie bars;

Figure 2 is a fragmentary side elevational view of the center joint forming mechanism, with the concrete omitted, and showing the anchoring members disposed longitudinally of the middle section of the joint body plate, with the anchoring members still disposed in the plane of the

middle section of the plate from which they are formed;

Figure 3 is a top plan view of a fragmentary portion of the improved center joint form, of the type illustrated in Figure 2 but with the anchoring members swung out of the plane of the form and disposed at right angles with respect thereto to project from opposite sides of the form;

Figure 4 is a fragmentary isometric view of the center joint form showing the anchoring members pivotally swung from the form body, with the opposite ends of the members of different shapes and projecting from opposite sides of the form body.

Figure 5 is a vertical transverse sectional view of a modified form of center joint form in which the body plate is substantially plain and has reinforcing ribs longitudinally formed thereon above and below the anchoring members which are swung out of the plane of the form plate with adjacent anchoring members swung out in opposite directions to stagger or alternate the like formed ends of the anchoring members.

Figure 6 is a fragmentary side elevational view of another modified form of center joint form in which the anchoring members are disposed transversely of the form plate and are pivotally swung out of the plane of the body plate into horizontal planes and with the adjacent anchoring members reversed with respect to one another;

Figure 7 is a fragmentary top plan view of the modified form of center joint form illustrated in Figure 6;

Figure 8 is a vertical sectional view of the modified form of center joint form with said section being taken on line VIII—VIII of Figure 6;

Figure 9 is a fragmentary side elevational view of another modified form of center joint forming mechanism wherein the body of the plate is formed with a center channel from which the anchoring members are cut vertically with respect to the plate permitting the anchoring members to be pivotally swung transversely in either direction to be disposed in horizontal planes; and

Figure 10 is a transverse sectional view of the center joint form, with said section taken on line X—X of Figure 9.

As shown on the drawings:

In the present invention the improved road center joint forming mechanisms, while being shown in several modified forms, are nevertheless all of a type in which the form body plate has cut or struck therefrom a plurality of anchoring members which are hingedly connected to the body plate to permit the anchoring members to be swung in either direction so that the ends of the anchoring members may project from opposite sides of the joint plate and be disposed in either vertical or horizontal planes to provide means for tying adjacent slabs of opposite road lanes together without resorting to the use of tie rods or the like.

While the joint forming mechanism is preferably designed for use as a center joint form, it is to be understood that the slab connecting units may be used for other purposes such as the tying together of adjacent blocks or slabs of concrete floors or the like.

The center joint form as illustrated in Figures 1 to 4 inclusive is adapted to be supported on a road subgrade 1 by means of a supporting base unit 2 which is seated longitudinally upon the center line of the subgrade 1 and is channeled for the reception of the lower margin of a center joint

body plate 3 constructed of sheet metal of a selected gauge. The center joint form is adapted to be embedded between adjacent concrete road slabs 4 and 5 forming parts of the opposite lanes of a concrete road which are to be transversely connected to one another. The body plate 3 has the longitudinal central portion thereof deflected or formed to provide a channel section consisting of a center plate 6 and inclined plates 7.

10 For the purpose of anchoring the opposite lane slabs 4 and 5 together, the center plate section 6 of the channel portion of the body plate has cut or stamped therefrom a plurality of spaced aligned anchoring members. Each of the anchoring members comprises a rectangular anchoring blade 8 and a tapered anchoring blade 9, the tapered narrow end of which is integrally connected with one end of the rectangular anchoring blade 8. The blades 8 and 9 are respectively cut from the plate section 6 along the lines 10 and 11, leaving uncut portions 12 which integrally and hingedly connect the inner end of the rectangular anchoring blade 8 with the center plate 6 on opposite sides of the inner narrow end of the tapered anchoring blade 9. The integral connecting sections 12 are adapted to serve as hinges whereby the blades 8 and 9 of each of the anchoring members are adapted to be pivotally swung out of the plane of the center plate section 6 into positions 20 preferably at right angles to the plane of the form body plate. The anchoring members may be pivotally swung out of the plane of the form plate so that all of the rectangular anchoring blades 8 project from the opposite side thereof. 25 If desired, the anchoring members may be pivoted about the hinge connections 12 so that the rectangular anchoring blades and the tapered anchoring blades of adjacent anchoring members may project in opposite directions.

30 After the channel-shaped center joint form is vertically supported longitudinally along the center line of the subgrade 1 by means of suitable supports 2, concrete is poured on opposite sides of the form to form the slabs 4 and 5 of opposite road lanes. The concrete embeds the anchoring blades 8 and 9 and ties the opposite road lanes together without the use of the ordinary type of tie rods or bars.

Figure 5 illustrates a cross-sectional view of a modified form of center joint form comprising a body plate 13 provided with longitudinally disposed upper and lower reinforcing ribs or beads 14 and 15 which alternately project from opposite sides of the plate 13 to reinforce the same. If desired, the ribs may project from the same side of the plate. Cut or struck from the longitudinal center portion of the body plate 13 are spaced anchoring members such as those illustrated and described in connection with Figures 1 to 4 inclusive and said members are designated by corresponding reference numerals.

Figures 6 to 8 inclusive illustrate another modified form of center joint form comprising a plain or flat body plate 16 which is adapted to be supported on a subgrade by means of supporting base members 2 or other suitable means. The modified form of body plate 16 is cut or stamped vertically at spaced intervals along the lines 17 and 18 to respectively form tapered anchoring blades 19 and rectangular anchoring blades 20. When the anchoring blades 19 and 20 are swung out of the plane of the plate 16, they leave the openings formed by the cuts 17 and 18. The narrow end of each of the anchoring blades 19 is integrally connected with one end of the ad-

adjacent rectangular anchoring blade 20 and the marginal portions of the blade 20 on opposite sides of the narrow end of the anchoring blade 19 are integrally connected with the plate 16 by portions which serve as hinges when the anchoring members are bent out of the plane of the body plate. The anchoring members may be bent out of the plane of the plate 16 with all of the tapered anchoring blades 19 disposed on one side of the plate and the rectangular anchoring blades 20 on the opposite side of the plate, or the anchoring members may be alternately bent out in opposite directions so that the tapered anchoring blades 19 and the rectangular anchoring blades 20 are staggered on opposite sides of the form plate.

Figures 9 and 10 illustrate another modified form of the center joint forming mechanism comprising a body plate 21 having the middle portion thereof shaped to provide a channel section 22 from which anchoring members are arranged transversely or across the channel section. The anchoring members are formed by cutting the channel section along the lines 17 and 18 to provide a tapered anchoring blade 19 and a rectangular anchoring blade 20 similar to the arrangement shown in Figures 1 to 8 inclusive.

It will accordingly be noted from the description hereinbefore given, that the improved center joint form consists of a joint forming body plate, either of plain or channeled construction or provided with reinforcing ribs or of any selected form of reinforcing means. The body plate has cut or struck therefrom dual anchoring members which are preferably disposed in the same plane and are adapted to be simultaneously bent or swung out of the plane of the body plate at substantially right angles thereto so that the anchoring blades are positioned either vertically or horizontally, depending upon whether the anchoring members are cut longitudinally from the body plate or transversely or across the width of the body plate.

The anchoring members are so formed that the middle portions thereof are hingedly or integrally connected with the body plate to permit the anchoring members to be pivotally swung transversely of the body plate as desired, to position all of the tapered anchoring blades on one side and the rectangular anchoring blades on the opposite side, or said anchoring blades may be projected so that the different shaped blades

are staggered with respect to one another on opposite sides of the body plate. It will accordingly be seen that the improved center joint form having each of the integral anchoring blades projecting from opposite sides thereof is adapted for tying adjacent or opposite slabs of adjacent road lanes together without the use of tie bars or the like.

It will, of course, be understood that various details of construction may be varied through a wide range without departing from the principles of this invention, and it is, therefore, not the purpose to limit the patent granted hereon otherwise than necessitated by the scope of the appended claims.

I claim as my invention:

1. A joint form comprising a plate body, a one-piece anchoring member cut therefrom and in the set up condition of the joint form extending from opposite sides of the plate body, the cut edges of the anchoring member on one side of the plate body being offset and discontinuous from the cut edges on the opposite side of said plate body to provide juncture portions between the plate body and the anchoring member, and said juncture portions forming integral bendable connecting hinges by which said anchoring member is bent out of the plane of said plate body.

2. A joint form comprising a plate body, a one-piece anchoring member cut therefrom and in the set up condition of the joint form extending from opposite sides of the plate body, the cut edges of the anchoring member on one side of the plate body being offset and discontinuous from the cut edges on the opposite side of said plate body to provide juncture portions between the plate body and the anchoring member, and said juncture portions forming integral bendable connecting hinges by which said anchoring member is bent out of the plane of said plate body, at least one portion of the anchoring member being of generally dovetail outline.
